ABSTRACT

An apparatus for regulating frost buildup in a refrigeration apparatus. A photocell and lamp are mounted to function within an open housing having essentially non-reflective interior wall surfaces. The housing is located adjacent the refrigeration apparatus permitting cold air to circulate therethrough and allow frost buildup on such surfaces. As frost forms thereon, illuminance intensity of the lamp light within the housing increases due to the light scattering characteristics of the frost causing the photocell to function to initiate the defrost cycle.

DEFROST SENSOR AND CONTROL CIRCUIT**BACKGROUND OF THE INVENTION****1. Field of the Invention**

This invention generally relates to defrosting controls for refrigeration apparatus and more particularly to an improvement in the apparatus for sensing and controlling frost buildup therein.

2. Description of the Prior Art

Refrigeration systems typically require periodic removal of frost from cooling elements which are used to absorb heat from the refrigerated zone since frost accumulation thereon decreases the cooling efficiency of the system. Various methods have been devised to control removal of such frost. For example, timers have been employed to initiate defrost cycle after passage of preselected time intervals. It should be noted that such devices lead to excessive cycling in dry weather when frost buildup is infrequent and to overloading in damp weather when frequency defrosting is required, and consequently, these timers have not been entirely satisfactory from a frost removal standpoint. More recently, various solid state and "hybrid" control circuits having frost sensing elements within the refrigerated area for sensing frost buildup have been adapted to coordinate cooling and defrosting functions in response to signals from such sensors. However, those proposed generally involve complicated sensing arrangements and circuitry, and although they serve the purpose for which they are intended, they are generally expensive to manufacture and maintain.

SUMMARY OF THE INVENTION

The general object of the present invention is to provide an improved frost control for regulating a defrost cycle in a refrigeration apparatus which circumvents the problems heretofore noted.

More specifically, it is an object to provide a frost control wherein a frost sensor is responsive to illuminance intensity generated by frost accumulation for energizing a defrost device to melt such frost.

In achieving these and other objects as will become apparent hereinafter, one embodiment of the present invention provides for a frost sensor comprising a lamp and photocell operatively positioned within a housing having generally non-reflective inner wall surfaces, such housing being positioned adjacent the cooling element of a refrigeration system and further includes a control responsive to the frost sensor for regulating refrigeration and defrost cycles. System air freely passes through the housing to form frost thereon concurrently with that on the cooling element. As frost accumulation builds up, the reflective characteristics of the inner housing walls increases and is sensed by the photocell which is positioned to receive indirect light which is emitted from the lamp within the housing and reflected and scattered off the white frost accumulation.

BRIEF DESCRIPTION OF THE DRAWINGS

In describing the present invention, reference will be made to the accompanying drawings forming a part of the instant disclosure wherein:

FIG. 1 is a perspective view of a typical refrigeration apparatus partially broken away to illustrate the frost sensor and control of the present invention in combination with such apparatus.

FIG. 2 is a perspective view partially broken away of the frost sensor device constructed in accordance with the present invention.

FIG. 3 is a schematic illustration of the refrigeration and defrost control circuit diagram embodying the present invention.

DETAILED DESCRIPTION OF INVENTION

With reference in more detail to FIG. 1 of the drawing there is shown a frost sensor device 10 mounted adjacent the cooling element 12 of a conventional refrigeration apparatus 13 for sensing frost conditions thereon and a control 14 having a circuit operatively connected to the sensor device 10 and refrigeration apparatus 13 for coordinating refrigeration and defrosting cycles, the details of which form a major portion of the invention.

Although the invention is directed particularly to the frost sensor device 10 and control 14, it will be helpful at the outset to describe generally the overall cooling operation of a refrigeration apparatus in which the new frost sensor device 10 is especially advantageous. Such an apparatus normally includes the aforementioned cooling element 12 comprising coils 16 through which a heat exchanging fluid or refrigerant flows and fins 18 mechanically attached to the coils 16 to enhance the heat exchange function. The coils 16 and fins 18 are positioned within the area to be refrigerated to absorb heat from air passing thereby. The heat exchange fluid removes such heat to a heat exchanging device 19 including a compressor motor CM in a manner commonly known and practiced throughout the industry. Efficiency of such a system drops considerably as frost accumulation and buildup occurs on the cooling element 12. Consequently, it is important to remove such frost to restore cooling power.

Having briefly described the general overall cooling operation of a refrigeration apparatus, it will be helpful to refer now to the constructional features of the frost sensor device 10 and control 14 of the present invention illustrated in detail in FIGS. 2 and 3 of the drawings. The frost sensor device 10 comprises a housing 20, a light source or lamp 22 and a photosensitive device such as a photoconductive cell 24 operatively affixed thereto. The control 14 is operatively connected to the device 10 and in conjunction therewith regulates the cooling and defrosting stages of the refrigeration apparatus 13 to maximize its cooling efficiency.

The housing 20 is constructed of a U-shaped, open ended member 26 secured to a mounting plate 28 in box-like fashion as shown in FIG. 2. The housing ends are open to permit air convection therethrough so that frost builds up therein concurrently with that accumulating on the coils 16 and fins 18 of the cooling element 12. The housing 20, with the exception of base portion 29, is constructed of a material having good heat conducting qualities such as aluminum so that it can instantaneously simulate the conditions of the cooling element 12 for accumulating frost. The base portion 29 upon which the lamp 22 and cell 24 are mounted is of low thermal conductivity material to aid in retention of lamp heat for maintaining lamp 22 and cell 24 clear from frost. The surface finish 30 of the inner housing wall 32 is slightly rough and irregular to enhance frost formation thereon and is prepared with a generally non-reflective coating such as black matte paint to reduce illuminance characteristics within the housing 20.

prior to frost buildup. The finish 30 is automatically cleared of frost and other foreign particles from the washing action of melted frost run-off and consequently is self-cleaning and maintenance-free.

The lamp 22 is mounted as shown in FIG. 2 to base portion 29 to provide illumination continuously within the housing 20 and is of the type that illuminates in all directions as opposed to focusing type lamps. A lamp of very low power requirement is selected to ensure long lamp life. It should be noted that lamp operation need not be continuous in which case a timer or other switching device (not shown) would be utilized to briefly energize the lamp at preselected time intervals thereby increasing lamp life. Under extreme environmental conditions, intermittent lamp operation may permit frost buildup thereon hampering its operation, and in such cases, a heater or small resistor R_L in FIG. 3 is connected in parallel with lamp 22 as shown in FIG. 3 to provide added heat. R_L is selected to perform this function without hindering frost accumulation on the housing wall surfaces 32.

The photocell 24 is designed to integrate light of low value within the housing 20 and is mounted generally adjacent and ahead of lamp 22 in a position to measure scattered and diffused light as shown in FIG. 2. The electrical resistance of the cell 24 decreases appreciably from exposure to increasing light radiation or illuminance within the housing 20. Consequently, cell 24 is selected to trigger the defrost cycle whenever such illuminance reduces its resistance to a reference level. Positioning of the cell 24 near the lamp 22 as shown in FIG. 2 generally assures no frost will build up on the cell 24 to interfere with its intended operation. Under extreme environmental conditions, R_L may be utilized to provide added heat to maintain both the lamp 22 and cell 24 clear from frost.

Consequently, it can be seen that, as frost builds up within the housing 20, such accumulation sharply increases scattering of light therein to an illuminance level to which the photoconductive cell 24 responds by turning on the defrost cycle described hereinafter with reference to FIG. 3.

Now referring to FIG. 3, the compressor motor CM is connected across A.C. supply lines L1 and L2 in series with main terminal A1 and K1 of a semiconductor device such as a bidirectional thyristor Q1 of the type sold under the trade name "Triac." Defrost heater H is similarly connected across lines L1 and L2 in series with the main terminal A2 and K2 of a second thyristor Q2 like Q1. The control gate G1 of Q1 is connected to line L1 in series with an electric thermostat TH, a resistor R1 and normally closed contacts RC1 of a relay RC. Control gate G2 of Q2 is connected to line L1 through resistor R2 and normally open contacts RC2 of relay RC.

When lines L1 and L2 are energized and the operating coil RC3 of relay RC is deenergized, it may be assumed that Q1 will be conducting if the electrical contacts of thermostat TH are closed. When Q1 is conducting, full wave A.C. current will be supplied to compressor motor CM. Also when relay RC is deenergized, Q2 will be held non-conducting to interrupt the flow of A.C. current to defrost heater H.

The remainder of the control depicted in FIG. 3, and now to be described, provides for the appropriate energization of relay RC to stop the refrigeration cycle and initiate defrosting of the cooling element 12, and pro-

vides deenergization of relay RC upon completion of such defrosting action.

The control for relay RC requires a source of rectified, filtered and regulated voltage which is provided by 5 a power transformer T having a primary winding P and a center tapped secondary winding S, half wave rectifier diodes D1 and D2, a capacitor C1, a resistor R3, and a zener diode D3. Primary winding P of the transformer is connected across A.C. lines L1 and L2, and 10 the opposite ends of secondary winding S are respectively connected through diodes D1 and D2 and resistor R3 to a positive potential conductor 33. Capacitor C1 is connected at its high potential plate to the point common between diodes D1 and D2 and resistor R3, and at its low potential terminal to center tap CT of winding S and to ground. Zener diode D3 has its anode connected to center tap CT and ground and its cathode to the point common between resistor R3 and conductor 33.

15 Conductor 33 is connected through a current limiting resistor R7 to a conductor 34 which provides a somewhat lower positive D.C. potential for certain of the relay control circuitry. Lamp 22 has one terminal connected through a conductor 35 and has its other terminal connected through a conductor 36 to ground. Photoconductive cell 24 is connected at one of its terminals through a conductor 38 to the gate G3 of a semiconductor device such as a programmable unijunction transistor Q3 of the type sold under the trade name of 20 "PUT." The cathode K3 of Q3 is connected to ground through conductor 36, and its anode gate A3 is connected to the point common between voltage divider resistor R4 and R5 which are connected in series across the conductors 34 and 36 and to the anode of a zener diode D4.

25 Control coil RC3 of relay RC is connected at one end to conductor 34 and at its other end to the cathode of zener diode D4. The zener break-down voltage of D4 is selected to be slightly higher than that across resistor R4 to prevent undesired current flow through coil RC3. A variable resistor R6 has its resistance element connected at one end to conductor 34 and at its other end to conductor 38. It will be seen that resistor R6 and cell 30 24 are thus connected in series across conductors 34 and 36 and provide a voltage divider for the gate G3 of PUT Q3.

35 The common point between voltage divider resistors R4 and R5 provides a fixed reference voltage V_a to which the anode A3 of PUT Q3 and the anode of zener diode D4 are subjected. With no frost buildup on the cooling element 12, it may be assumed that the resistance of cell 24 due to the low intensity of illuminance will be sufficiently high to subject gate G3 to a resultant voltage V_g which is higher than the reference voltage V_a impressed on anode A3. Consequently, PUT Q3 will be held nonconducting.

40 A capacitor C2 is connected between conductors 34 and conductor 38 and gate G3 to suppress transient voltages that might otherwise cause false triggering of PUT Q3. A diode D5 is connected across relay coil RC3 and zener diode D4 to clamp induced voltages when coil RC3 is suddenly deenergized at the end of a defrost cycle.

45 Now let it be assumed that during operation of compressor motor CM, frost builds up on cooling element 12. This results in increased illuminance in the housing 20 as aforesaid and consequently photoconduc-

tive cell 24 decreases in resistance thereby decreasing the magnitude of voltage V_g to which gate G3 of PUT Q3 is subjected. When voltage V_g decreases to the value of voltage V_a , PUT Q3 is turned "on" and is latched in "on," a fully conducting state in a manner similar to a silicon controlled rectifier. Conduction of PUT Q3 brings the potential of its anode A3 close to ground, and the potential drop across zener diode D4 exceeds its breakdown voltage to cause current flow through relay coil RC3. Opening of contacts RC1 and closure of contacts RC2 then results. Consequently, Q1 is rendered non-conducting to deenergize motor CM, if then energized, and Q2 is rendered conducting to energize defrost heater H. Accordingly, any refrigeration cycle then existing is stopped and the defrost cycle initiated.

As the defrost cycle proceeds, frost on the cooling element 12 will be melted, thereby decreasing the illuminance in housing 20. This results in an increase in resistance of photoconductive cell 24, but even though it rises to a value causing voltage V_g to rise to its initial value exceeding that before obtaining at the junction of resistors R4 and R5 and R4, it cannot render PUT Q3 conducting again until the flow of current through the anode A2 of Q3 is reduced below its "valley" current value.

The remaining portion of the control circuitry now to be described provides for stopping of the control flow through relay coil RC3 and PUT Q3 when the defrost cycle has effected removal of a sufficient amount of frost from cooling element 12.

A semiconductor device such as an N-P-N transistor Q4 has its collector connected to conductor 34 and its emitter to ground. The base of Q4 is connected in series with a zener diode D6 to the point common between the lower end of variable resistor R8 and the upper terminal of a positive temperature coefficient thermistor PTC which is mounted on cooling element 12. Resistor R8 and thermistor PTC act as a voltage divider and subject the cathode of zener diode D6 to a voltage which increases with the resistance of thermistor PTC.

Now let it be assumed as the defrost cycle proceeds, that the frost has melted and the cooling element continues to rise in temperature due to the heat generated by the heater H. When the temperature of thermistor PTC reaches its curie point, approximately 65°F, a very sharp rise in its resistance occurs causing a corresponding sharp rise in voltage at the cathode of zener diode D6. When this latter voltage exceeds the breakdown voltage across zener diode D6, current will then flow from conductor 33 through resistor R8, and diode D6 into the base of Q4 to render the latter substantially fully conducting.

When transistor Q4 is conducting, current flowing through resistor R7 is shunted through the collector-emitter circuit of Q4 to ground, thereby shutting off current flow through relay coil RC3 and PUT Q3 and resistors R4 and R5. Consequently, coil RC3 is deenergized and contacts RC1 reclose and contacts RC2 reopen. Accordingly, defrost heater H is deenergized to stop the defrost cycle and the gate circuit of Triac Q1 is again readied to effect conduction of the latter whenever the thermostat TH functions to complete the gate circuit.

It will be observed that with flow of current into the anode A3 of PUT Q3 stopped, the latter is then effec-

tively "reset" to a nonconducting state and will again be effective to initiate the defrost cycle in the manner hereinbefore described.

If desired, Triacs Q1 and Q2 can be replaced by electromagnetic relays or contactors, and the contacts RC1 and RC2 of relay RC would then be appropriately connected in the energizing circuits for the operating coils of such relays or contactors in a well-known manner.

10 In summary, it should be appreciated by one skilled in the art that the present invention provides a simple, inexpensive and highly responsive frost sensor device and control therefor for sensing frost and initiating a defrost cycle only when needed within a refrigeration apparatus.

15 It will be apparent that various details of the illustrated forms of the present invention may be varied without departing from the inventive concept. It will accordingly be understood that it is intended to embrace within the scope of this invention such modifications as may be embraced by the skill of the art.

We claim:

20 1. In a frost sensor for refrigeration apparatus having a cooling element therefor which refrigerant is circulated, and which is susceptible to frost build-up thereon, and a defrost device adapted when energized to remove frost from said cooling element, the combination comprising:

25 a housing having irregular inner wall surfaces of low reflective ability on which frost can accumulate and being adapted to be mounted adjacent said cooling element in frost forming relationship therewith.

30 a light source operatively mounted to said housing to illuminate said inner wall surfaces of said housing;

35 a photosensitive device operatively mounted to said housing to sense the level of illuminance therein when frost builds up on said inner wall surfaces and responsive to initiate removal of frost from said cooling element when illuminance reaches a preselected level within said housing, and said photosensitive device being directed away from said light source to prevent direct impingement of light thereon.

40 45 50 2. A frost sensor according to claim 1 wherein said light source emits scattered light therefrom to be diffused within said housing for sensing by said photosensitive device.

55 3. A frost sensor according to claim 1 wherein said photosensitive device is positioned adjacent and ahead of said light source to prevent light from being directly transmitted from said light source to said photosensitive device.

60 4. The combination according to claim 1 together with a heating means operatively connected to said housing for providing heat to said photosensitive device and said light source to maintain said device and source free from frost accumulation.

65 5. In a refrigeration apparatus, the combination with a cooling element through which refrigerant is circulated and upon which frost is susceptible of build-up, means energizable to circulate refrigerant through said cooling element and energizable to cause melting of frost on the latter, of means including control means for energizing and deenergizing the first mentioned

means and said defrost means, said control means having a frost sensor comprising:

- a. a partially open housing mounted adjacent said cooling element and having inner walls in frost receiving relation thereto;
- b. a light source mounted in said housing and illuminating said inner wall surfaces thereof;
- c. a photosensitive cell mounted in said housing and arranged to be responsive to change in the level of illuminance in said housing as frost forms on said inner wall surfaces;
- d. first semiconductive means responsive to said photosensitive cell to cause said defrost means to be energized and said first mentioned means to be de-energized when illuminance reaches a predetermined level within said housing;
- e. second semiconductor means responsive to decrease of illuminance in said housing resulting from melting of frost to render said first semiconductor means inactive and thereby effect deenergization of said defrost means and activation of said first mentioned means to resume the refrigeration process as demanded, and
- f. third and fourth semiconductor means in circuit respectively with first mentioned means, said defrost means, and said first semiconductor means, said third and fourth semiconductor means being responsive to actuation and deactuation and said first semiconductor means to effect corresponding energization and deenergization of said defrost means and said first mentioned means, selectively.

6. A refrigeration apparatus according to claim 5, wherein said first semiconductor means comprises a programmable unijunction transistor having anode, gate and cathode terminals, wherein said control means further includes an electromagnetic relay which is en-

ergizable and deenergizable to provide response of said third and fourth semiconductor means alternately, wherein the energizing winding of said relay is in circuit with the anode-cathode circuit of said unijunction transistor, and wherein the gate terminal of the latter is in circuit with said photoconductive cell and is responsive to the resistance of the latter decreasing to a predetermined level to cause conduction of said unijunction transistor and energization of the relay energizing winding.

7. A refrigeration apparatus according to claim 6 wherein said second semiconductor means is a transistor having its emitter-collector terminals connected in circuit with said unijunction transistor and said relay and wherein said control means further includes a temperature sensitive device contiguous with said cooling element and in circuit with said unijunction transistor and second semiconductor transistor to shunt essentially all current flow away from said unijunction transistor to ground at the end of a defrost cycle thereby deenergizing said unijunction transistor and said relay to cause said third semiconductor means to be deenergized to end defrost cycle and said fourth semiconductor means to be energized to resume the refrigeration process as demanded by the system.

8. A refrigeration apparatus according to claim 7, wherein said third and fourth semiconductor devices are bidirectional thyristors and wherein said temperature sensitive device is a positive temperature coefficient thermistor.

9. The combination according to claim 5, together with a heating means operatively connected to said housing for providing heat to said photosensitive cell and said light source to maintain said cell and source free from frost accumulation.
